UNITED STATES PATENT OFFICE

2,661,528

CAN OPENER

George H. Coplen, Cripple Creek, Colo.

Application June 30, 1952, Serial No. 296,290

2 Claims. (Cl. 30—20)

1
This invention relates to a can opener, and has for its principal object the provision of a simple, light-weight, portable can opener which will quickly and easily cut away and remove the lid of a can of any type or shape.

Another object of the invention is to provide a can opener which will prevent the severed lid from dropping into the can.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a left side elevation of the improved can opener, illustrating it in place on a typical can;

Fig. 2 is a right side elevation thereof; and

Fig. 3 is a front end view of the improved can opener.

The improved opener employs an elongated guide bar 10 along which a carriage member 11 may be freely slid. The forward extremity of the bar 10 is turned downwardly to form a pivot member 12, and the lower extremity of the pivot member is sharpened and extends forwardly to form a can-piercing point 13. The rear extremity of the bar 10 terminates in a suitable lower handle 14.

The carriage member 11 supports a stationary transverse shaft 15 which extends oppositely outward from both sides of the carriage member. A ratchet wheel 18 is rotatably mounted on the shaft 15 at one side of the carriage member 11. A bifurcated forward extremity 16 on an upper handle member 17 is rotatably mounted on the opposite extremities of the shaft 15 and extends on opposite sides of the carriage member 11 and retains the ratchet wheel 18 thereagainst.

The ratchet wheel 18 is provided with peripheral ratchet teeth 19 and with inclined or beveled teeth 20 about its inner periphery. A leaf ratchet spring 21 is secured on the bottom of the handle 17 by means of suitable rivets 23 or other attachment means. The forward extremity of the ratchet spring 21 is positioned to contact the bottom of the extremity 16 and to engage the peripheral ratchet teeth 19 of the ratchet wheel 18. A click spring 24 is secured on the carriage member 11 and positioned to en-

gage the ratchet teeth 19 to prevent return movement of the ratchet wheel 18. A return spring 30 is coiled about the shaft 15 and connected between the latter and the handle 17 to urge the latter upwardly when released.

A fixed stub shaft 25 extends vertically downward from the carriage member 11, and rotatably supports a traction roller 26. The roller 26 is held in place on the shaft in any desired manner, such as by riveting or upsetting the lower extremities of the shaft 25. The traction roller is formed with bevel teeth 27 at its top which mesh with the teeth 20 of the ratchet wheel 18 and with elongated, inclined, can-gripping teeth 28 at its lower portion. The gripping teeth 28 are formed on a cone with the smaller diameter downwardly. A cutting knife blade 29 is fixed to, and extends downwardly from, the carriage member 11 in closely spaced relation to the periphery of the traction roller 26.

In use, the can-piercing point 13 is forced through the top of a can, such as indicated at 31 in Fig. 1, at approximately the center thereof. The handle 14 is then swung downwardly to place the pivot member 12 in a pivoting position in the can. As the handle is swung downwardly, the carriage 11 is moved to position the point of the blade 29 immediately inside the bead or rim of the can, and the knife is forced through the metal of the can by forcing the handle 14 downwardly. This causes the bead or side of the can to wedge between the inclined teeth 28 of the traction roller and the cutting blade 29.

The handle 17 is now squeezed downwardly toward the handle 14 by gripping the two handles in one hand. Each downward movement of the handle 17 will cause the ratchet spring 21 to rotate the ratchet wheel 18. This will in turn rotate the traction roller 26, through the intermeshing of the teeth 20 and 27, to cause the roller to travel around the periphery of the can to force the cutting blade around the can to sever the top therefrom. Each time the hand grip is released, the return spring 30 will lift the handle 17 to allow the ratchet spring 21 to obtain a new grip on the teeth 19 until the top is completely severed from the can. The severed top can now be lifted from the can by means of the hooked point 13.

It is desired to call attention to the fact that it is not essential that the pivot 12 be at the center of the can, nor is it essential that the can be round, since the carriage member 11 will move in and out on the bar 10 to follow the periphery 55 of a can of any given shape.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. The combination with a can opener of the type having a pointed, hooked guide bar with a 10 slidable carriage member on said guide bar and a can-cutting blade projecting downwardly from said carriage member, of means for forcing said can-cutting blade around the periphery of a can, comprising: a fixed stub shaft extending vertically downward from said carriage member adjacent said cutting blade; a traction roller of greater diameter at its mid-portion than at its bottom and top rotatably mounted on said shaft; elongated, inclined, can-gripping teeth extending from the greater diameter mid-portion to the 20 bottom of said roller adapted to engage the outer periphery of a can; beveled gear teeth extending from the greater diameter mid-portion to the top of said roller in alignment with said can-gripping teeth; a stationary, horizontal, transverse shaft projecting from said carriage member at right angles to and above said guide bar; a wheel rotatably mounted on said transverse shaft; beveled teeth formed on said wheel and meshing with the beveled teeth on the top of said 30

traction roller; an upper handle member hingedly mounted on said transverse shaft; peripheral ratchet teeth formed in said wheel; a ratchet pawl mounted on said upper handle member and engaging said ratchet teeth to rotate said wheel; and a lower handle member formed on said guide bar in gripping relation to said upper handle member so that when said handle members are forced together, said wheel will be rotated.

10 2. The combination in a can opener of the type described in claim 1 of a bifurcated forward extremity on said upper handle member hingedly mounted on the opposite extremities of the transverse shaft and extending on opposite sides of said carriage member and acting to retain said wheel thereagainst; and a click member mounted on said carriage and engaging said ratchet teeth to prevent return rotation of said ratchet wheel.

GEORGE H. COPLEN.
